UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 18,735, dated November 13, 1888.

Application filed October 18, 1888. Serial No. 228,468. Term of patent 14 years.

To all whom it may concern:

Be it known that I, HERMAN IHLENBURG, a citizen of the United States, and a resident of Philadelphia, Pennsylvania, have invented a new and original Design for a Font of Type, of which the following is a specification.

My design is clearly shown in the accompanying typographic impression, to which reference is made.

- 10 The font of type is termed "Fancy Script." The letters are shaded and slightly inclined. The letters of the upper-case are formed of a series of shaded scroll-lines. The letters A, B, D, F, K, M, N, P, R, T, U, V, W, X, and Y have extending from their tops heavily shaded scroll, and the primary upright lines of the letters A, H, K, M, and N terminate in heavily shaded scrolls or curves. The remaining let-

ters are so formed as to preserve the appearance of heavy shading at the top and base. ²⁰

The shading of the lower-case letters is in keeping with the shading of the upper-case letters, in that the shading extends around the tops and bottoms of the letters.

The numerals of the font are in keeping with the upper and lower case letters.

I claim as my invention—

The design for a font of type, substantially as shown and described.

In testimony whereof I have signed my name ³⁰ to this specification in the presence of two subscribing witnesses.

HERMAN IHLENBURG.
